Howson & Howson

UNITED STATES PATENT OFFICE

CHARLES T. GRIFFITH, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA

STOCKING FORM

Application filed December 17, 1927. Serial No. 240,847.

My invention relates to certain improvements in stocking forms, in which means is provided for locating the seam at the back of the stocking and at the center thereof when 5 pressed.

The object of my invention is to so design a form that the seam can be located substantially at the center without using right and left hand forms. This object I attain in the 10 following manner, reference being had to the accompanying drawings, in which:

Figure 1 is a side view of stocking form illustrating my invention;

Fig. 2 is a large sectional view on the line 15 2—2, Fig. 1;

Fig. 3 is an enlarged view showing the location of the seam in the back of the stocking; and

Fig. 4 is a modification, showing the board 20 beveled at the foot, as well as the back of the leg portion.

Referring to the drawings, 1 is a stocking form. This form is made of metal in the present instance and is solid and flat, as shown in 25 Fig. 2. The front edge 2 of the form is beveled on both sides, while the rear edge 3 is beveled on one side only. This places the sharp rear edge 4 at one side of the center *a* of the form so that when a stocking is placed 30 over the form, the seam *b* of the stocking *a* can be located substantially at the center of the form, as shown in Fig. 3.

In Fig. 1, I have shown the back edge of the form 1 beveled from the heel 5 to the end 35 6, while in Fig. 4, I have illustrated a modification, in which the form 1*a* is beveled from the end 6*a* to the toe 7. The extent of the bevel will depend upon the type of stocking to be stretched upon the form.

40 I claim:

A stocking form having flat parallel sides and a single flat face along one of its edges, said single flat face extending from one to the other of said flat parallel sides at an acute 45 angle with respect to one of the said parallel sides of the form.

CHARLES T. GRIFFITH.
